CONTROL DEVICE FOR FLUID FUEL
BURNERS

William J. Russell, Jeannette, Pa., assignor to Robertshaw-Fulton Controls Company, Greensburg, Pa., a corporation of Delaware

Application March 3, 1954, Serial No. 413,751

13 Claims. (Cl. 236—1)

This invention relates to combination controls for gaseous fuel burners wherein the temperature controlling device and the pilot flame failure cutoff both operate upon a single control valve. In this respect, the device is similar to that disclosed in U. S. Patent No. 2,361,945 to W. F. Jackson wherein the automatic pilot control embodies thermomagnetic means responsive to the extinguishment of the pilot flame for causing the control valve to close in the event it was being held open by the thermostat.

The present invention is particularly adapted, although not limited, for use with gas burning space heaters and the like whereby room temperatures may be controlled within precise limits. The thermally responsive element is preferably of the hydraulic type which lends itself with the utmost flexibility to a variety of different installations. The majority of features found advantageous in prior devices of this general type are retained in this invention.

In devices of this type, it is desirable to provide conduit means for by-passing the control valve to maintain a low flame on a main burner when the control valve has been closed in response to a temperature condition in the room being heated. However, in the event of pilot flame failure with such an arrangement, unburned fuel escaping through the by-pass conduit would create a dangerous condition. Thus, in addition to the foregoing features, the present embodiment provides for automatic shut off of all main burner fuel, including that flowing in the by-pass conduit, in the event of pilot flame failure. Moreover, the single valve for dual control purposes is not subjected to damage when the automatic shut off occurs and provides a safeguard against valve sticking which may occur where a separate cutoff valve is provided and infrequently operated. A safe lighting feature is provided by preventing fuel flow through the main control valve and the by-pass conduit during resetting of the automatic shutoff device.

A further object of this invention is to prevent fuel flow through the by-pass conduit means when the thermally responsive element is adjusted to maintain a relatively low temperature.

With these and other objects in view, the invention is embodied in the combined thermostat and automatic pilot control by including, in a single casing, a main control valve, a pilot fuel valve and a by-pass valve with the main control valve operable by both a thermoelectric pilot control and a thermal element responsive to room temperatures. The thermal element is operable through a lever device on one side of the control valve while the thermoelectric pilot control is operable on the main control valve from the opposite side thereof. The thermostat lever is normally biased for opening the control valve, but operation of the thermal element will overcome this bias upon a selected room temperature being reached. However, since the pilot control may operate automatically due to extinguishment of the pilot burner flame, the control valve may at any time be closed irrespective of the condition of the thermal element.

The pilot fuel valve controls fuel flow to the pilot burner and to the by-pass valve and is in turn controlled by the thermoelectric pilot control to be closed upon pilot flame failure. A manually operable resetting device 5 is associated with the thermoelectric pilot control for resetting the same while holding the main control valve and the by-pass valve closed and the pilot fuel valve open. The by-pass valve is also operatively associated with the temperature setting mechanism of the thermal element to 10 be closed when such mechanism is adjusted to set the thermal element to actuate the main control valve at a relatively low temperature.

Other objects and advantages will appear from the following description taken in connection with the accompanying drawings wherein:

Fig. 1 is a schematic view showing, in cross section, a control device embodying this invention; and

Fig. 2 is a fragmentary top view of the device shown in Fig. 1.

Referring more particularly to the drawings, the control device comprises a casing 10 provided at one end with a lateral inlet opening 12 adapted for connection to a source (not shown) of fluid fuel and at the other end with an outlet opening 14 adapted for connection to a main burner (not shown). Formed in the central portion of the casing 10 is a valve chamber 16 which communicates with the inlet 12 through a main shut-off plug valve 18 and with the outlet 14 through an aperture 20 formed in a valve seat 22. The valve seat 22 is thus positioned in the flow passage of fuel flowing from the inlet 12 to the outlet 14 through the valve chamber 16.

Aligned with the aperture 20 of the valve seat 22 is a bore 24 formed in a wall of the casing 10. A valve stem 26 extends slidably through the bore 24 and a disc valve member 28 is mounted on the valve stem 26 for movement therewith between open and closed positions relative to the valve seat 22. The valve member 28 is normally biased toward the valve seat 22 by a spring 30 acting between the casing 10 and a collar 32 secured to the valve stem 26.

The valve stem 26 extends out of the casing 10 into engagement with flexible amplifying levers 34 of a snap-action clicker mechanism of well known form including a thrust element 36 which serves to impart snap-action movement to the amplifying levers 34 and valve stem 26. The amplifying levers 34 are sufficiently rigid to overcome the bias of the spring 30 and move the valve member 28 away from the valve seat 22 when actuated by the thrust element 36. However, when an additional biasing load is applied to the valve member 28 through thermoelectric means to be described hereinafter, the amplifying levers 34 will merely flex and will impart no movement to the valve member 28. Thus, the flexible levers 34 provide an override mechanism. If desired, the amplifying levers 34 may be relatively rigid and an override mechanism may be provided within the valve stem 26 in a manner well known in the art and as disclosed in U. S. Patent 2,607,529 to R. F. Garner.

Thermally responsive means for operating the valve member 28 through the clicker mechanism 34, 36 is provided and is housed within a housing 38 which is secured to the exterior of the casing 10. This means includes an actuating device in the form of a bellows 40 which is movable in a path substantially parallel with the axis of the valve stem 26. The usual capillary tubing 42 is connected at one end to the bellows 40 and projects from the housing 38 for connection to a bulb 44. As is customary in thermal elements of the type described, the bulb 44, capillary tube 42, and bellows 40 contain a thermally expansive fluid which will serve to expand the bellows 40 in response to increased temperatures sensed by the bulb 44.

The bellows 40 is supported on one end of a pivoted lever 46 which is biased into engagement therewith by a coil spring 48 seated on the housing 38. The lever 46 is provided with an abutment 148 engageable with the thrust element 36 of the clicker mechanism. Consequently, clockwise movement of the lever 46, as viewed in Fig. 1 of the drawings, under the bias of the spring 48 will cause upward movement of the valve stem 26 and valve member 28.

The thermally responsive means is adapted to be adjusted from the front of the casing 10 to set the temperature at which the valve member 28 will be operated. The adjusting means takes the form of a stem 50 which threadedly engages the casing 10 and extends therethrough into operative engagement with the bellows 40. The stem 50 carries on its projecting end the usual dial 52 carrying indicia "High," "Medium," "Low," and "Night off" for selective registry with a registry point 54 on the casing 10. Preferably, the "Night off" indicia indicates a temperature setting lower than the "Low" setting.

Thermoelectric means is provided for moving the valve member 28 to closed position upon the occurrence of certain conditions to be described and irrespective of the thermal condition of the thermal element 40-44. To this end, a magnet housing 56 is slidably mounted in the valve chamber 16 in axial alignment with the valve stem 26 and valve member 28. An electromagnet comprising a horseshoe frame 58 is mounted within the magnet housing 56 and is provided with the usual winding 60. The winding 60 is connected through suitable conductors 62 to a thermocouple 64.

An armature 66 is supported within the magnet housing 56 on an armature stem 68 which projects to the exterior of the magnet housing 56 and which is disposed in axial alignment with the valve stem 26. The armature 66 is removable between attracted and released positions relative to the pole faces of the magnet frame 58 and is biased toward the released position by a spring 70 acting between the magnet housing 56 and a collar 71 secured to the armature stem 68. In the released position of the armature 66, the armature stem 68 will be positioned in engagement with the valve member 28 with the spring 70 acting to hold the valve member 28 in engagement with the valve seat 22 despite any forces which may be exerted on the valve stem 26 by the amplifying levers 34 of the clicker mechanism.

As is well known, the electrical energy generated by the thermocouple 64 will be insufficient to attract the armature 66 from its released position but will be sufficient to hold the same in attracted position after the usual resetting operation has been conducted. Consequently, manual resetting means is provided for positioning the armature 66 in its attracted position in engagement with the pole faces of the magnet frame 58. To this end, a plunger 72 is secured to the magnet housing 56 in axial alignment with the armature stem 68 and one end thereof projects out of the casing 10. The projecting end of the plunger 72 carries a push button 74 and a spring 76 acting between the push button 74 and the casing 10 serves to bias the assembly of the magnet housing 56, plunger 72 and push button 74 away from the valve member 28. Thus, the spring 76 serves to hold the armature stem 68 out of engagement with the valve member 28 when the armature 66 is in its attracted position.

A pilot burner outlet passage 78 is formed in the casing 10 and adapted for connection to a conduit 80 which communicates with a pilot burner 82. The pilot burner 82 is disposed adjacent the thermocouple 64 and the rate of fuel flow to the pilot burner 82 is regulated by a suitable plug valve member 84 mounted in the pilot outlet passage 78. The pilot outlet passage 78 communicates with a valve chamber 86 formed in the casing 10 adjacent the valve chamber 16 and communi-

cating therewith through a passage 88. Thus, fuel may be supplied to the pilot burner 82 from the inlet 12 through the valve chamber 16, passage 88, valve chamber 86, outlet passage 78, and conduit 80.

Flow of fuel to the outlet passage 78 is under the control of pilot valve means disposed within the valve chamber 86. This means is here shown as comprising an annular valve seat 90, formed on the casing 10 within the valve chamber 86, and a disc valve member 92 movable into and out of engagement with the valve seat 90. The valve member 92 is biased toward the valve seat 90 by a spring 94 and is also operatively associated with the thermoelectric means to be positioned in its open position during the resetting operation and whenever the armature 66 is in its attracted position.

The operative connection between the valve member 92 and the thermoelectric means is here shown as including a valve stem 96 depending from the valve member 92 and projecting, through a bore 98 formed in the casing 10, into the valve chamber 16. The valve stem 96 engages one end of a lever 100 which is pivoted intermediate its ends on the armature stem 68. The other end of the lever 100 is pivotally connected to a bracket 102 which depends from the magnet casing 56 and is secured thereto for movement therewith. With such an arrangement, downward movement, as viewed in Fig. 1, of the magnet housing 56 during the resetting operation will cause downward movement of the bracket 102 and counterclockwise rotation of the lever 100 to move the valve stem 96 upward and carry the valve member 92 out of engagement with the valve seat 90.

Upon completion of the resetting operation, the magnet housing 56 moves upward under the bias of the spring 76, carrying the attracted armature 66 and armature stem 68 therewith. Upward movement of the armature stem 68 will cause the lever 100 to move bodily upward so that the same will continue to hold the valve member 92 out of engagement with the valve seat 90.

To maintain a low flame at the main burner when the main control valve 28 is closed by the action of the thermal element 40-44, by-pass means is provided for supplying fuel to the outlet 14. This means takes the form of a by-pass passage 104 formed in the casing 10 to communicate with the outlet 14 and with the pilot outlet passage 78 downstream of the pilot valve 90, 92. The rate of fuel flow through the by-pass passage 104 is controlled by a plug valve member 106 disposed therein.

Fuel flow in the by-pass passage 104 is also controlled by by-pass valve means which takes the form of a valve seat 108 formed on the casing 10 within the passage 104 and a disc valve member 110 movable into and out of engagement with the valve seat 108. The valve member 110 is biased away from the valve seat 108 by a spring 112 to normally hold the valve member 110 in a fuel flow permitting position. However, means is provided for moving the by-pass valve member 110 into engagement with the valve seat 108 to prevent fuel flow through the by-pass passage 104 during the resetting operation and whenever the temperature setting dial 52 is moved to a relatively low temperature setting as indicated by the indicia "Night off" thereon.

More particularly, a valve stem 114 is secured to the valve member 110 and extends through a bore 116 formed in the casing 10, the valve stem 114 projecting beyond the front panel of the casing 10. Extending across the front panel of the casing 10 and mounted thereon by a pivot 118 is an operating lever 120. The operating lever 120 is disposed adjacent the push button 74, extends beneath the temperature setting dial 52 and overlies the projecting end of the valve stem 114.

The operating lever 120 is adapted to be rotated in a clockwise direction as viewed in Fig. 1 to depress the valve stem 114 and move the valve member 110 into engagement with the valve seat 108 by a cam element 122 which is secured to the stem 50 to rotate therewith.

The configuration of the cam element 122 and the angular relation thereof with the temperature setting knob 52 is such that the above described clockwise rotation of the operating lever 120 will occur upon movement of the temperature setting knob 52 to bring the indicia "Night off" into registry with the mark 54. Thus, for relatively low temperature settings of the temperature setting knob 52, a flame is not maintained at the main burner at all times but is present only when the main control valve member 28 is opened by operation of the thermal element 40-44.

To prevent fuel flow through the by-pass passage 104 during the resetting operation and thus assure safe lighting, a lug 124 is secured to the operating lever 120 to extend laterally therefrom with the end portion thereof being positioned beneath the push button 74. Depression of the push button 74 during the resetting operation will move the same into engagement with the lug 124 and impart clockwise movement, as viewed in Fig. 1, to the operating lever 120 to depress the valve stem 114 and move the valve member 110 into engagement with the valve seat 108.

In the event it is desirable to eliminate the flow of fuel through the by-pass passage 104 in all temperature settings of the knob 52, manually operable means is provided for holding the valve member 110 in engagement with the valve seat 108. This means is here shown as comprising a threaded stem 126 threaded into a tapped recess 128 formed in the casing 10. The stem 126 extends substantially normal to the operating lever 124 and is positioned adjacent thereto so that a knob 130 secured to the projecting end of the stem 126 will overlie a portion of the operating lever 120. A cam surface 132 formed on the underside of the knob 130 is positioned to engage the operating lever 120 when the stem 126 is screwed into the tapped recess 128. Such engagement will be effective to impart clockwise rotation, as viewed in Fig. 1, to the operating lever 120 to depress the valve stem 114 and move the valve member 110 into engagement with the valve seat 108.

Operation

As shown in the drawings, the various parts of the device are positioned for preventing fuel flow to the main and pilot burners. The control device is placed in operative condition by manual operation of the push button 74 which is depressed to move the magnet housing 56 downward, thereby bringing the pole faces of the magnet frame 58 into engagement with the armature 66 and pivoting the lever 100 in a counterclockwise direction to position the pilot valve member 92 out of engagement with the valve seat 90. It should be observed that such depression of the push button 74 will hold the by-pass valve member 110 in fuel flow preventing position regardless of the setting of the temperature setting knob 52 through the engagement of the lug 124 by the push button 74 as previously described. Thus, fuel will flow only to the pilot burner 82.

The fuel issuing from the pilot burner 82 is then lighted and the hot junction of the thermocouple 64 becomes heated. As soon as the thermocouple 64 develops sufficient current to energize the winding 60 of the electromagnet, manual pressure on the push button 74 may be released and the armature 66 will be retained in its attracted position, being moved out of engagement with the main control valve member 28 upon return movement of the magnet housing 56 to its initial position under the bias of the spring 76.

The dial 52 may be adjusted to the desired temperature setting. Operation of the dial 52 from "Night off" setting to "Low" or "Medium" will be in a counterclockwise direction and will serve to withdraw the stem 50 slightly from the casing 10. As the bellows 40 is under the bias of the spring 48, a corresponding axial movement of the bellows 40 will occur accompanied by

clockwise rotation of the lever 46 also under the bias of the spring 48. As the spring 48 is stronger than the clicker mechanism 34, the lever 46 is enabled to exert a thrust upon the valve operating stem 26 and, assuming that the room temperature is below the dial setting, the valve member 28 will be snapped to its open position by operation of the clicker mechanism.

Flow of fuel through the outlet 14 to the main burner can then occur and this burner becomes ignited from the pilot burner 82. Heating of the space to the required temperature then continues until the bulb 44 responds to the increased temperature. The fluid contained in the hydraulic thermal element consequently expands and causes a corresponding expansion of the bellows 40 in a well known manner. Such expansion overcomes the bias of the spring 48 and causes a counterclockwise movement of the lever 46. Such movement of the lever 46 causes return snap action of the clicker mechanism permitting spring 30 to close the valve member 28 against its seat 22.

Upon closing of the main valve member 28, fuel flow to the main burner will be reduced to a minimum as determined by flow through the by-pass passage 104. As soon as the temperature sensed by the bulb 44 drops below that for which the thermostat has been set, then the position of the parts is reversed and the valve member 28 resumes its open position as previously described.

In the event it is desired to maintain a relatively low temperature within the space being heated, the temperature setting dial 52 is rotated in a clockwise direction to position the indicia "Night off" in registry with the mark 54. Such movement of the dial 52 will screw the stem 50 into the casing 10 forcing the bellows 40 downward against the bias of the spring 48. As is well known in devices of this type, such movement of the bellows 40 will result in its actuating the valve member 28 at relatively low temperatures. As the temperature setting dial 52 is moved to the "Night off" position, the cam 122 is moved into engagement with the operating lever 120 to cause clockwise movement of the same about the pivot 118 and closing movement of the by-pass valve member 110 as hereinbefore described. Thus, fuel is prevented from flowing in the by-pass passage 104 in the "Night off" position of the temperature setting dial 52, and flame will be present at the main burner only when the main control valve 28 is in its open position as determined by temperatures sensed by the thermal element 40-44.

If desired, the "Night off" setting may be such that contraction of the bellows to its limit of contraction will be ineffective to position the lever 46 to open the main control valve 28. With such an arrangement, no flame can be produced at the main burner when the dial 52 is in the "Night off" position regardless of temperatures sensed by the thermal element 40-44.

In the event that the pilot burner 82 is extinguished, the thermocouple 64 ceases to generate current, causing deenergization of the winding 60 and movement of the armature 66 to its released position under the bias of the spring 70. Such movement of the armature 66 serves to move the armature stem 68 into engagement with the valve member 28 and hold the same in engagement with the valve seat 22 regardless of temperatures sensed by the thermal element 40-44. Downward movement of the armature stem 68 also serves to pivot the lever 100 in a clockwise direction to permit downward movement of the valve stem 96 and movement of the pilot valve member 92 into engagement with the valve seat 90 under the bias of the spring 94. It should be noted that upon closing of the pilot valve member 92, no fuel can flow in the by-pass passage 104 since the same is in communication with the pilot outlet passage 78 downstream of the pilot valve 90, 92. Thus, upon flame failure at the pilot burner 82, no fuel can flow to the main burner or to the pilot burner 82 and the 100% shut-off feature is retained in this invention.

It will be understood that many changes may be made in the details of construction and arrangement of parts without departing from the scope of this invention as defined in the appended claims.

It is claimed and desired to secure by Letters Patent:

1. In a control device for fluid fuel burners, the combination of a casing having main inlet and outlet passages, a valve seat intermediate said passages, temperature responsive valve means cooperable with said valve seat for controlling fuel flow from said inlet to said outlet passage, said casing having a pilot burner outlet passage communicating with said inlet passage, valve means in said pilot passage for controlling fuel flow therethrough, said casing having a by-pass passage communicating with said main outlet passage and said pilot passage downstream of said last named valve means, said last named valve means being adapted to control the flow of fuel through said by-pass passage, and thermoelectric means for controlling the operation of both said valve means.

2. In a control device for fluid fuel burners, the combination of a casing having main inlet and outlet passages, a valve seat intermediate said passages, temperature responsive valve means cooperable with said valve seat for controlling fuel flow from said inlet to said outlet passage, means including an adjustable element movable through a range of settings for setting the temperature to which said valve means will respond, said casing having a pilot burner outlet passage communicating with said inlet passage, valve means in said pilot passage for controlling fuel flow therethrough, said casing having a by-pass passage communicating with said main outlet passage and said pilot passage downstream of said last named valve means, valve means in said by-pass passage and movable between positions for controlling fuel flow therethrough, thermoelectric means for controlling the operation of said temperature responsive and said pilot valve means, and means for moving said by-pass valve means from one to another of said positions in response to movement of said adjustable element to one of said temperature settings.

3. In a control device for fluid fuel burners, the combination of a casing having main inlet and outlet passages, a valve seat intermediate said passages, temperature responsive valve means cooperable with said valve seat for controlling fuel flow from said inlet to said outlet passage, means including an adjustable element movable through a range of settings for adjusting the temperature to which said valve means will respond, said casing having a by-pass passage communicating with said main inlet and outlet passages, valve means in said by-pass passage and movable between positions for controlling fuel flow therethrough, and means for moving said by-pass valve means from one to another of said positions in response to movement of said adjustable element to one of said temperature settings.

4. A control device as claimed in claim 3 wherein said last named means is operable to move said by-pass valve means to a position for preventing fuel flow in said by-pass passage when said adjustable element is moved to a relatively low temperature setting.

5. A control device as claimed in claim 3 wherein said adjustable element is rotatable and cam means movable therewith is provided for moving said by-pass valve means to a position for preventing fuel flow through said by-pass passage when said element is moved to a relatively low temperature setting.

6. In a control device for fluid fuel burners, the combination of a casing having main inlet and outlet passages, a valve seat intermediate said passages, temperature responsive valve means cooperable with said valve seat for controlling fuel flow from said inlet to said outlet passage, means including an adjustable element movable through a range of settings for adjusting the

temperature to which said valve means will respond, said casing having a pilot burner outlet passage communicating with said inlet passage, valve means in said pilot passage movable between positions for controlling fuel flow therethrough, said casing having a by-pass passage communicating with said main outlet passage and said pilot passage downstream of said last named valve means, valve means in said by-pass passage and movable between positions for controlling fuel flow therethrough, thermoelectric means including an electromagnet having an armature movable between attracted and released positions and operatively associated with said temperature responsive and pilot valve means for holding the same in fuel flow preventing positions while said armature is in said released position, and resetting means operable for positioning said armature in said attracted position and said pilot valve means in fuel flow permitting position, said reset means being operatively associated with said by-pass valve means for holding the same in fuel flow preventing position during the resetting operation.

7. A control device as claimed in claim 6 and including means for moving said by-pass valve means to fuel flow preventing position in response to movement of said adjustable element to a selected portion of said range of temperature settings.

8. Control means for fluid fuel burning appliances having a main and a pilot burner and a source of fuel, comprising temperature responsive valve means movable between open and closed positions for controlling fuel flow from the source to the main burner, by-pass valve means movable between open and closed positions for controlling fuel flow from the source to the main burner, means including an adjustable element movable through a range of settings for adjusting the temperature to which said temperature responsive valve means will respond, and means for moving said by-pass valve means from one to another of said positions in response to movement of said adjustable element to one of said temperature settings.

9. Control means for fluid fuel burning appliances having a main and a pilot burner and a source of fuel, comprising temperature responsive valve means movable between open and closed positions for controlling fuel flow from the source to the main burner, auxiliary valve means movable between open and closed positions for controlling fuel flow from the source to the pilot burner, conduit means for supplying fuel from said auxiliary valve means to the main burner, by-pass valve means in said conduit means movable between open and closed positions for controlling fuel flow from said auxiliary valve means to the main burner, and thermoelectric means for controlling the operation of said temperature responsive and said auxiliary valve means.

10. Control means as claimed in claim 9 and including means having an adjustable element movable through a range of settings for adjusting the temperature to which said temperature responsive valve means will respond, and means for moving said by-pass valve means from one to another of said positions in response to movement of said adjustable element to one of said temperature settings.

11. Control means as claimed in claim 9 wherein said thermoelectric means includes an electromagnet having an armature movable between attracted and released positions and operatively associated with said temperature responsive and auxiliary valve means for holding the same in fuel flow preventing position while said armature is in said released position, and resetting means operable for positioning said armature in said attracted position and said auxiliary valve means in fuel flow permitting position, said reset means being operatively associated with said by-pass valve means for holding the same in fuel flow preventing position during the resetting operation.

12. Control means for fluid fuel burning appliances having a main and a pilot burner and a source of fuel, comprising temperature responsive valve means movable between open and closed positions for controlling fuel

flow from the source to the main burner, by-pass valve means movable between open and closed positions for controlling fuel flow from the source to the main burner independently of said temperature responsive valve means, means responsive to a flame at the pilot burner and having an operative position for holding said temperature responsive valve means in said closed position, resetting means for setting said flame responsive means in an inoperative position, and means operatively associated with said resetting means for holding said temperature responsive and said by-pass valve means in said closed positions during the resetting operation.

13. Control means for fluid fuel burning appliances having a main and a pilot burner and a source of fuel, comprising first conduit means for supplying fuel from the source to the main burner, valve means movable between

open and closed positions for controlling fuel flow in said first conduit means, second conduit means for supplying fuel from the source to the main burner independently of said first conduit means, means responsive to a flame at the pilot burner and having an operative position for holding said valve means in said closed position, resetting means for setting said flame responsive means in an inoperative position, and means for preventing fuel flow through both said conduit means during the resetting operation.
